[57] ABSTRACT

The four-stroke internal combustion engine comprises a stator having induction and exhaust ports, a rotor rotatable in the stator and defining cylinders with the stator in which pistons connected to a crankshaft are slideable. A transmission device interposed between the crankshaft and rotor produces a given relative speed of rotation therebetween. The feature of the engine is that additional ports, comprising an inlet port and outlet port, are provided in the stator and each piston and corresponding cylinder cooperate with these additional ports in the course of a part of each revolution of the rotor to perform a pumping function.

FIG. 1

FIG. 2

FIG. 3

ROTARY CYLINDER INTERNAL COMBUSTION ENGINE

The present invention relates to a four-stroke internal combustion engine whose cylinders are arranged radially in a rotor.

A first known arrangement employed in such engines consists in maintaining the pistons constantly applied against a fixed centre cam whose profile is such that each piston undergoes two to-and-fro movements per revolution of the rotor. These arrangements have two serious drawbacks: on one hand, the speed of rotation of the rotor is high and gives rise to piston ring problems very difficult to solve and, on the other, the linear contact on the cam results in excessive Hertz pressures.

In another arrangement the pistons of each cylinder are connected by a connecting rod to the crankpin of a crankshaft, the ratio between the speeds of rotation of the rotor containing the cylinders and the crankshaft being such that each piston undergoes an even number of to-and-fro movements per revolution of the rotor. In these engines, the desire for maximum compactness is at the cost of balance. Indeed, there is incompatibility between great compactness, which can only be achieved with rather large inclinations of the connecting rods, and good balance which requires small inclinations.

Moreover, there is disclosed, in particular in the Certificate of Addition No. 95,879 attached to French Pat. No. 1,453,504, an internal combustion engine comprising a crankshaft provided with an eccentric crankpin, four fixed cylinders arranged in the form of a cross and having axes perpendicular to the axis of the crankshaft, two pairs of pistons each of which pair of pistons is mounted to rotate on a journal of a common balancing element which is mounted to rotate on the crankpin, the axes of the journals and crankpin being parallel and contained in the same plane, and the offset of the crankpin from the axis of the crankshaft being equal to one half of the distance between said journals. Such an engine has a practically perfect balance. Unfortunately, as it is necessary to place at the head of each cylinder a cylinder head having induction and exhaust valves and to provide means for controlling these valves, there results an assembly which is very large and mechanically complex.

Now it is known that in an engine having four cylinders arranged in the form of a cross in which the pistons located on the same axis are rigidly interconnected, if the cylinders are rotated about an axis perpendicular to the plane of the cylinders, the number of to-and-fro movements effected by each piston per revolution of the cylinder block is necessarily odd. This is why this design of an engine having rotating cylinder blocks has been proposed heretofore only for two-stroke engines but never for four-stroke engines.

An object of the invention is to provide an internal combustion engine having rotary cylinders operating on the four-stroke cycle which is particularly compact and as perfectly balanced as possible owing in particular to the elimination of the connecting rod-crank systems.

According to the invention, there is provided a four-stroke internal combustion engine comprising a stator having induction and exhaust ports, a rotor rotatably mounted in the stator and defining cylinders in which are received pistons connected to a crankshaft, and a

transmission device between the crankshaft and the rotor for establishing therebetween a given relative speed, wherein the stator has two additional ports, namely an inlet port and a delivery port, with which additional ports each cylinder and piston assembly cooperates in the course of a part of each revolution of the rotor for performing a pumping function.

The invention is more particularly applicable to an engine having a crankshaft provided with an eccentric crankpin, four cylinders arranged in the form of a cross and having axes perpendicular to the axis of the crankshaft, two pairs of pistons, each pair being mounted to rotate on a journal of a common balancing element which is rotatably mounted on the crankpin, the axes of the journals and of the crankpin being parallel and contained in the same plane and the offset of the crankpin from the axis of the crankshaft being equal to one half of the distance between said journals.

Another feature of this engine is that the rotor rotates in the stator about an axis perpendicular to the axes of the cylinders, the transmission device between the rotor and the crankshaft being such that the ratio between the speeds of rotation of the crankshaft and rotor is a positive or negative even whole number different from +2.

In a preferred embodiment, the direction of rotation of the crankshaft is opposite to that of the rotor and its speed of rotation is four times higher so that it is possible to employ, per revolution of the rotor, four to-and-fro movements of each piston to achieve two complete four-stroke drive cycles and one to-and-fro movement of the piston to ensure the pumping through said additional ports.

The invention will be described in more detail herein-after with respect to a preferred embodiment with reference to the accompanying drawings in which:

FIG. 1 is a cross-sectional view of an engine according to the invention;

FIG. 2 is a sectional view taken on line 2-2 of FIG. 1, and

FIG. 3 is a diagram showing the different phases of the cycle of operation of a cylinder and piston assembly for one revolution of the rotor.

The engine according to the invention comprises a stator 1 having a roughly cylindrical outer shape made in two parts 2, 3 which are assembled in a longitudinal joint plane 4. This stator defines an inner volume defined by a spherical surface 5 having the center 0. This inner volume is defined laterally, on one side by a side wall 6, and, on the other, by a side wall 7 and a planet gear carrier 8.

In the inner volume of the stator 1 there is disposed a rotor 9 made in two parts 10, 11 assembled in a transverse joint plane 12. The semi-rotor 10 has a bearing portion 13 journaled in a bearing 14 of the side wall 6 and the semi-rotor 11 has a bearing portion 15 journaled in a bearing 16 of the side wall 7.

The two semi-rotors surround four cylinder liners 17, 18, 19, 20 which are in opposed relation in pairs on two axes Y-Y, Z-Z intersecting at the centre 0. Each liner is positioned by a rib 21 engaged in a groove 22 of the rotor 9. A crankshaft 23 is journaled in a bearing 24 of the rotor and in a bearing 25 of the planet gear carrier 26. The bearings 14, 16, 24 and 25 have a common axis X-X passing through the centre 0 of the spherical inner surface 5 of the stator 1.

A gear pinion 26 connected to rotate with the crankshaft 23 meshes with planet gears such as 27. Each of

these gears 27 is freely rotatable on a pin 28 carried by the planet gear carrier and meshes with a ring gear 29 secured to the rotor 9. The number of teeth of the ring gear 29 is equal to four times the number of teeth of the gear pinion 26 so that the speed of rotation of the crankshaft is four times that of the rotor in absolute value, but in the opposite direction.

The crankshaft 23 has a crankpin 30 which is offset or eccentric a distance e from the axis X—X. Mounted on the crankpin 30 to be freely rotatable is a balancing element 31 having a cylindrical centre bearing portion 32 and two cylindrical lateral bearing portions 33. The bearing portion 32 is offset to one side of the axis of the crankpin 30 to an extent e and bearing portions 33 are offset to the opposite side of the axis of the crankpin to the same extent e .

The bearing portion 32 is journalled in a bore formed in a strut 34 rigidly interconnecting two opposed pistons 35, 36 which are respectively slidably mounted in the cylinders 17 and 19. The centre of the bearing portion 32 is, on the axis Y—Y, at equal distances from the two pistons 35 and 36.

The bearing portions 33 are journalled in bores formed in two halves of a strut 37 rigidly interconnecting two opposite pistons 38, 39 respectively slidably mounted in the cylinders 18 and 20. The centre of the bearing portion 33 is, on the axis Z—Z, at equal distances from the two pistons 38 and 39.

The volumes defined in each cylinder between the pistons and the spherical surface 5 of the stator constitute the combustion chambers of the engine. A seal between the pistons and the cylinders is afforded by piston rings 40 and a seal between the rotor and the stator is afforded around each cylinder by circular rings 41 disposed in grooves of each liner such as 17.

The stator half 2 has externally two semicircular passages 42 receiving the carbured gases by way of an orifice 43 and communicating with the interior of the stator by way of induction ports 44, 45.

Exhaust ports 46, 47 are also formed in the stator 1 which also serves as a support for the spark plugs 48, 49.

The angular distance between the two plugs, or between the induction ports, or between the exhaust ports, is equal to $2/5$ of a circumference, namely 144° . These various ports and the plugs are moreover suitably disposed along the periphery of the stator with respect to the upper dead centre and lower dead centre positions of the pistons respectively designated by the letters $H_1, B_1, H_2, B_2, \dots H_5, B_5$, the rotor rotating in the direction of arrow F_1 .

The stator half 3 has an inlet port 50 and a delivery port 51 which are placed circumferentially between the exhaust port 47 and the induction port 45. The port 50 is placed between the positions H_5 and B_5 and the port 51 between the positions B_5 and H_1 .

The engine just described operates in the following manner:

For each revolution of the crankshaft with respect to the rotor which is assumed to be fixed, each piston undergoes one to-and-fro movement in each cylinder.

As the rotor is itself driven in rotation at a quarter of the speed of the crankshaft and in the opposite direction, for each revolution of the rotor each piston undergoes five to-and-fro movements in its cylinder.

As can be seen in FIG. 3, four to-and-fro movements correspond to two complete cycles of a four-stroke combustion engine (H_1, H_3 and H_3, H_5), and the fifth

to-and-fro movement is employed as an air pump (H_5 and H_1).

The driving cycles are the following:

H_1, B_1 induction; B_1, H_2 compression; H_2 ignition; H_2, B_2 expansion; B_2, H_3 exhaust etc. . .

The pump operation corresponds to: H_5, B_5 suction; B_5, H_1 delivery.

Depending on whether the inlet port 50 or delivery port 51 is connected to the atmosphere, the pumping operation can be employed as a source of pulsating air or as a source of suction in very diverse applications:

Thus in an automobile vehicle, the pulsating air can be mixed with the exhaust gases to ensure their post-combustion. This arrangement has moreover the advantage of furnishing a supply of air proportionate to the speed of rotation of the engine.

If the pump is employed as a source of suction, the vacuum produced can be employed for various control devices, for example for braking. This application is particularly indicated when the engine according to the invention operates in accordance with the Diesel cycle, since in this case there is insufficient suction in the suction manifold for the controls.

It must be understood that the invention is not limited to the embodiment described. Thus in accordance with the general definition of the invention, different ratios may be provided between the speeds of rotation of the rotor and crankshaft.

Note, moreover, that an exact balancing of the assembly can be achieved very simply, since the resultant of the forces of inertia due to the reciprocating masses passes through the crank arm and has a constant modulus for a given speed. This balancing can then be achieved by means of counterweights whose centre of gravity is diametrically opposed to the axis of the crankpin 30 with respect to the axis of the crankshaft 23. The counterweights may be located on the crankshaft (52) and/or on the flywheel (at 53) and/or on a pulley (at 54).

Having now described my invention what I claim as new and desire to secure by Letters Patent is:

1. In a four-stroke internal combustion engine comprising a stator having induction and exhaust ports, a rotor mounted to rotate in the stator and defining with the stator cylinders, a crankshaft mounted to rotate in the stator, pistons slidably mounted in the cylinders and connected to the crankshaft, and a transmission device interposed between the crankshaft and the rotor to produce between the crankshaft and the rotor a given relative speed of rotation; the provision in the stator of additional ports comprising an inlet port and a delivery port, with which additional ports each piston and corresponding cylinder are cooperable in the course of a part of each revolution of the rotor for performing a pumping function.

2. An engine as claimed in claim 1, wherein the crankshaft has an eccentric crankpin, and a balancing element is rotatably mounted on the crankpin and defines journals which are parallel to the axis of the crank and contained in the same plane as the axis of the crankpin, there being four cylinders arranged in the form of a cross and having their axes perpendicular to the axis of the crankshaft, and two pairs of pistons, each pair of pistons being mounted to rotate on a journal of the balancing element, the offset of the crankpin from the axis of the crankshaft being equal to one half of the distance between said journals.

3. An engine as claimed in claim 1, wherein the rotor rotates in the stator about an axis perpendicular to the axes of the cylinders, the transmission device between the rotor and the crankshaft being such that the ratio between the speeds of rotation of the crankshaft and rotor an even whole number different from +2.

4. An engine as claimed in claim 3, wherein said whole number is negative.

5. An engine as claimed in claim 3, wherein said whole number is positive.

6. An engine as claimed in claim 1, wherein the direction of rotation of the crankshaft is opposed to that of the rotor and its speed of rotation is four times higher so that it is possible to employ, per revolution of the rotor, four to-and-fro movements of each piston to

achieve two complete four-stroke drive cycles and one to-and-fro movement of the piston to perform the pumping function through said additional ports.

7. An engine as claimed in claim 1, wherein the whole of the moving parts of the engine are balanced by means of counterweights the centre of gravity of which counterweights is diametrically opposed to the axis of the crankpin with respect to the crankshaft axis, the counterweights being carried by the crankshaft.

8. An engine as claimed in claim 7, wherein the crankshaft carries the counterweights through the medium of an element secured to the crankshaft to rotate with the crankshaft.
